CLAIM

The ornamental design for a device for repairing and
strengthening vehicles or the like, as shown and de-
scribed.

DESCRIPTION

FIG. 1 is a right side elevational view of a device for
repairing and strengthening vehicles showing my new
design, the left side elevational view being a mirror
image thereof;

FIG. 2 is a top plan view;

FIG. 3 is a front elevational view;

FIG. 4 is a rear elevational view; and

FIG. 5 is a bottom plan view thereof.

The broken line showings of vehicle ramps and attaching
mechanism in FIGS. 2, 3 and 6 are environmental
only and form no part of the claimed design.
